DESIGN FOR A RELISH TRAY

Harry I. Kleinberg, Pittsburgh, Pa.

Application June 8, 1946, Serial No. 130,529

Term of patent 3½ years

(Cl. D44—10)

To all whom it may concern:

Be it known that I, Harry I. Kleinberg, a citizen of the United States, residing at Pittsburgh, in the county of Allegheny and State of Pennsylvania, have invented a new, original, and ornamental Design for a Relish Tray, of which the following is a specification, reference being had to the accompanying drawing, forming a part thereof.

Figure 1 is a top plan view of a relish tray, showing my new design.

Figure 2 is a bottom plan thereof.

Figure 3 is a side elevational view of the relish tray with a portion of the latter being broken away.

I claim:

The ornamental design for a relish tray, as shown.

HARRY I. KLEINBERG.
